UNITED STATES PATENT OFFICE.

BENJAMIN F. RIX, OF KALAMAZOO, MICHIGAN, ASSIGNOR TO R. ARTHUR STONE, OF SAME PLACE.

TWO-WHEELED VEHICLE.

SPECIFICATION forming part of Letters Patent No. 358,752, dated March 1, 1887.

Application filed September 18, 1886. Serial No. 214,070. (No model.)

To all whom it may concern:

Be it known that I, BENJAMIN F. RIX, of Kalamazoo, in the county of Kalamazoo and State of Michigan, have invented new and useful Improvements in Two-Wheeled Vehicles; and I do hereby declare that the following is a full, clear, and exact description thereof, reference being had to the accompanying drawings, which form a part of this specification.

10 This invention relates to new and useful improvements in two-wheeled vehicles; and the object of the invention is to adapt the vehicle to be used with either thills or a plate, as desired; and to this end my invention consists in the peculiar construction and arrangement of the parts, as hereinafter described.

In the drawings which accompany this specification, Figure 1 is a side elevation of a road-cart embodying my invention. Fig. 2 is 20 a plan thereof, and Fig. 3 is a cross-section on line 1 1 in Fig. 2.

E is the axle, provided with the wheels A, and B are the side bars, which are identical in every respect with the ordinary thills used 25 in connection with this class of vehicles, except that they do not reach farther in front than is necessary to receive the front cross-bar which carries the whiffletree. At the rear ends these side bars are secured to the axle in 30 the usual manner.

D D are two cross-bars, the one farthest in front carrying the whiffletree and the other being directly in the rear thereof, each consisting of an upper and lower chord secured 35 together by spreader-bars and bolts to form a stiff vertical truss, which at the ends is bolted or clamped to the under side of the side bars, preferably by the same bolt which secures the ends of the chords together.

40 F are thills, which, as shown in the drawings, are of the usual kind, except that they need not reach any farther to the rear than is necessary to secure their rear ends in any suitable manner upon the cross-bars D in the angle formed with the side bars; but, if it is desired to use a pole, the rear end of such pole may be easily inserted between the chords of the cross-bar and secured thereto in any suitable manner. I preferably choose to make 45 such pole bifurcated at the rear, such bifurca-

cations being secured together by spreader-bars b and bolts, as shown. This construction not only combines lightness and strength, but it gives increased facility for securing the pole to the cross-bars, the spreader-bars of which 55 form lateral supports for such pole.

By using hook-bolts m, or other detachable connections for securing the pole to the cross-bars, it will be seen that the pole may be readily made detachable, and if similar means 60 are provided to secure the thills to their respective side bars, the cart may be used either with a pole or with thills, as desired.

S is the seat. a are the seat-bars. C is the riding-spring, and e are hangers supporting 65 the riding-spring; but I merely choose to show these parts to illustrate a complete cart, and lay no claim on their construction or arrangement. It is also obvious that my invention may be used in connection with many other 70 constructions in present use.

What I claim as my invention is--

1. In road-carts, the combination, with a 75 pole or thills, of side bars fixedly secured at the rear end to the axle and extending forwardly to the front cross-bar, and two truss cross-bars adapted to receive the ends of a pole between their upper and lower chords, substantially as described.

2. In road-carts, the combination, with side 80 bars fixedly secured at their rear ends to the axle and extending forwardly to the front cross-bar, of two truss cross-bars secured at their ends to the under side of the side bars and adapted to receive the ends of a pole between 85 their upper and lower chords, substantially as described.

3. In combination, the side bars, B, rigidly secured at their rear ends to the axle and extending forwardly to the front cross-bar, the 90 trussed cross-bars D, secured at their ends to the under side of the side bars, and the pole e, detachably secured between the upper and lower chords of the cross-bars, all substantially as described.

BENJAMIN F. RIX.
